(57) **CLAIM**

The ornamental design for an oxygen applicator for a skin treatment system as shown and described.

DESCRIPTION

FIG. 1 is a front elevational view of an oxygen applicator for a skin treatment system, in accordance with the present design;

FIG. 2 is a right side elevational view thereof;

FIG. 3 is a rear elevational view thereof;

FIG. 4 is a left side elevational view thereof;

FIG. 5 is a top plan view thereof;

FIG. 6 is a bottom plan view thereof; and,

FIG. 7 is a perspective view thereof from the front right side. The broken line for the section of the tubing connected to at the bottom depicts environment only and forms no part of the claimed design.
